DESIGN FOR A SHOE BUCKLE OR SIMILAR ARTICLE

David Levin, New York, N. Y.

Application July 30, 1934, Serial No. 52,735

Term of patent 7 years

To all whom it may concern:

Be it known that I, DAVID LEVIN, a citizen of the United States, residing in New York, in the county of New York, and State of New York, have invented a new, original, and ornamental Design for a Shoe Buckle or Similar Article, of which the following is a specification, reference being had to the accompanying drawing, forming part thereof.

Fig. 1 is a perspective view of a buckle embodying the present design, shown in closed position, a portion of the strap to which the buckle is attached being shown in dotted lines;

Fig. 2 is a similar view showing the buckle in open position.

I claim:

The ornamental design for a shoe buckle or similar article, as shown and described.

DAVID LEVIN.
